CLAIM

The ornamental design for an automobile tire, as shown and described.

DESCRIPTION

FIG. 1 is a perspective view of an automobile tire showing our new design, it should be understood that the tread pattern is repeated throughout the circumference of the tire;

FIG. 2 is an end elevational view thereof; and

FIG. 3 is a side elevational view thereof, the opposite side being substantially the same as that shown.

FIG. 1

FIG. 2

FIG. 3
